NONREFILLABLE CONTAINER

Myer Sigman, Cleveland, Ohio

Application August 6, 1936, Serial No. 94,646

5 Claims. (Cl. 215—14)

My invention relates generally to containers for confining liquid bodies. The invention particularly relates to liquid containers used for packaging and dispensing goods of trade-marked or standardized quality.

The invention has for an object to provide a liquid container having means for preventing a filling thereof subsequent to the removal of the original contents. Another object of the invention is to provide a container having means whereby an attempted filling thereof, subsequent to the removal of the original contents, is indicated, said means thereby serving in a tell-tale capacity.

15 A still further object of the invention is to provide means preventing refilling thereof which also serves to somewhat restrict the flow of original contents from the container to an easily manipulatable flow thereby facilitating precise measurement of dispensed quantities as well as 20 many other advantages. Said means further fulfills another object of the invention in that it tends to prevent the entry of insects attracted by the contents of the container and the entry 25 of dust particles and the like contained in the atmosphere surrounding the container.

The invention has for a particular object to provide a container having elements installable by the packer and removable only upon destruction which tend to prevent refilling of the container and which trap certain quantities of liquid used in attempted refilling to indicate to the user or prospective purchaser such attempted refilling. Another particular object of the invention is to provide a container having means including a valve element which is adapted to be located in a closed position after the original packaging of the container and is adapted to be moved by the user to an open position. Thus, 30 the container may be not only sealed by the customary closure, but the contents may be sealed from contact with the closure by said valve element. Said valve element is so constructed and related to other elements as to permit only the 35 one operation of the opening, thus serving to indicate a previous tampering with the container, if opened on receipt, and warning the user thereby.

Another particular object of the invention is 40 to provide a container having said elements performing said described functions without interfering with the ordinary dispensing flow of the original contents thereof, except to modulate said dispensing flow to a practical and manipulative 45 degree. A still further particular object of the

invention is to provide a container for spirituous liquors and the like having relatively simple but efficient means to insure against the likelihood of substitution of the contents thereof and sale of said substitute in a trade-mark bearing container to the damage of the original packer and the fraud of the purchasing public.

The invention consists in other features and advantages which will appear from the following description and upon examination of the drawings. Structures containing the invention may partake of different forms and still embody the invention. To illustrate a practical application of the invention, I have selected a non-refillable container and one of its modified forms as examples of the various structures and details thereof that contain the invention and shall describe the selected structures hereinafter, it being understood that variations may be made without departing from the spirit of the invention. The particular structures selected are shown in the accompanying drawings.

Fig. 1 of the accompanying drawings illustrates a perspective view of a preferred form of container embodying my invention and described hereinafter for purposes of illustration, in accordance with the statute. Fig. 2 illustrates a view of an enlarged longitudinal section of a part of the container shown in Fig. 1, the elements being shown in a different relative position as hereinafter described. Fig. 3 illustrates a view of a section taken on the plane of the line 3—3 indicated in Fig. 2. Fig. 4 illustrates a view of a modified form of construction parts being shown in section to better illustrate said form. Fig. 5 illustrates the structure illustrated in Fig. 4, parts being shown in section and in different relative position to other parts than as shown in Fig. 4.

My invention may be embodied in a container 40 formed of a material, such as glass, and having a containing body portion 1 which is surmounted by a dispensing throat portion 2. The throat 2 has a lip 3 which communicates through the throat with the interior of the body portion 1. 45 Thus, a liquid, such as that illustrated at 5, contained within the body portion 1 may be dispensed through the throat and over the lip 3.

Disposed intermediate the lip 3 and the interior of the body portion are the elements comprising a means tending to prevent filling the body portion after the original contents, the liquid 5, has been removed. Preferably, the said elements are located in the throat portion and form in conjunction therewith a means for in-

dicating an attempt at refilling of the container with liquid by trapping a quantity thereof in the throat. As illustrated in the drawings, the throat 2 is provided with an annular seat 7 which may 5 be formed by constricting the throat at a point where it joins the body portion 1. Said seat 7 is adapted to receive and support in sealed relation to the inner sides of the throat an insertable stopper or wall element 8. The element 8 10 is preferably discular in shape formed from a material, such as cork, substantially impervious to liquid and capable of limited contraction and expansion. The element 8, therefore, separates the interior of the body portion 1 from the 15 throat 2.

The throat is further provided with a second annular seat 9. The seat 9 is preferably recessed in the wall of the throat and is adapted to receive and support in sealed relation thereto a second insertable stopper or wall element 10. The element 10 20 is likewise preferably of discular shape and formed of cork. By thus locating the element 10 with reference to the element 8, a chamber 11 is therebetween formed within the 25 throat. The element 10 also defines an outer throat 13.

In order to convey the liquid contents 5 within the body portion to the outer throat 3 and to a dispensing point of the lip, a conduit or stem 30 pipe 12 is provided and extends through openings 14 and 15 formed in the elements 8 and 10 respectively. The stem 12 is preferably formed of glass having its ends closed. One end of the stem extends into the interior of the body 1 and 35 has side openings 16, and the other end extends well into the outer throat 13 and has side openings 17 formed in spaced relation to the outer surface of the element 10. Thus, it will be seen that the liquid contents may be conveyed from 40 the interior of the body to the lip 3.

Preferably the openings 14 and 15 are of a diameter to tightly clasp the stem 12 as to prevent, in pouring, the entry of the contents 5 into the chamber 11, but large enough to permit an 45 endwise movement of the stem with respect to the elements 8 and 10. Thus, it will be seen, as illustrated in Fig. 1, the stem may be so located during original packaging and before opening by the customer or user, so that the openings 16 are located in registration with portions of the element 8 surrounding the opening 15 and may be closed thereby. When it becomes desirable to dispense the contents, the user merely by insertion of some suitable tool, such as a pencil, into 50 the outer throat 13 engages the stem to move the same with respect to the elements 8 and 10 until the openings 16 are no longer in registration with the element 8 and are located in an uncovered open position within the body of the 55 container, such as is illustrated in Fig. 2 of the drawings. Thus, an effective valve is provided which can be operated only by the user and only once by him, namely from a closed to an open position. If desired, a suitable header 20 may 60 be provided at the outermost end of the stem 12 to provide a bearing on which the tool for moving the stem may be placed.

The header 20 may be formed of glass and is 70 preferably of discular shape, having a diameter but slightly less than the inner diameter of the outer throat 13. The header may be connected to the stem 12 in any suitable manner, such as illustrated at 21. The header not only provides a means for bearing the pressure of application of the applied tool in opening the valve, as

described, but also acts as a barrier to the insertion of tools below or on the inner side of the header to tamper with the other elements located in the outer throat. The header also acts in conjunction with the passageway of the 5 stem 12 to modulate the flow of the contents 5 outwardly to one of a degree and depth that enables easy manipulation and measurement of portions and the like. Said flow is directed by the header 20 along the surface of the outer 10 throat 13 and over the lip in a shallow stream, permitting inflow into the container of quantities of air to occupy the space from which the contents have been displaced.

If desired, the stem may be further provided 15 with means safeguarding the withdrawal thereof from its installed relation to the elements 8 and 10. Said means may be embodied in a shoulder portion 24 which limits the outward movement of the stem 12 with respect to the element 10 20 retained in the recessed seat 9. The shoulder 24 is so positioned as to engage said element 10 when an attempted withdrawal is effected. The shoulder portion 24 is preferably formed by an enlarged mass or body 25 surrounding the stem 25 12 and integral therewith. The body 25 may be provided with a second shoulder portion 26 which is adapted to engage the element 8 to limit the inward movement of the stem 12 as shown in Fig. 2, as when uncovering the stem 30 openings 16.

Thus, it will be seen that the original contents 5 may be dispensed from time to time with a well and desirable modulation of flow, the elements 8 and 10 and header 20 acting to prevent 35 the entrance of insects and dust into the body of the container. It will be further seen that after the said original contents have been withdrawn from the container, a refilling of the same is rendered difficult by reason of the inaccessibility of the openings 17 in the stem 12 and the baffling effect of the header 20.

In order to indicate an attempted refilling of the container, as by pouring a refilling liquid into the outer throat 13 with the expectant eventuality that said liquid will flow through the openings 17 and stem 12 to within the container body, an indicating trap is provided. Said trap comprises the chamber 11 which communicates with the outer throat 13 and lip 3 through a passageway formed in a pipe or stem 30. The stem 30 is preferably formed of glass and extends through the opening 31 formed in the element 10. The outer end 33 of the stem 30 is closed and is provided with side openings 32 in somewhat 55 spaced relation to the outer surface of the element 10 but more proximate thereto than the openings 17 of the stem 12. The closed end 33 and the spacial relation between the openings 32 and element 10 tend to prevent entrapment of 60 portions of the original contents in the chamber 11 during repeated dispensing tippings of the container. However, when a refilling of the container is being attempted by pouring the refilling liquid into the outer throat 13, the refilling liquid is sustained in the outer throat 13 by the element 10 until the surface level of the liquid is raised to a plane common with the portion of the stem 30 having the openings 32. Thereupon, the refilling liquid enters the chamber 11 immediately indicating the attempted refilling by the presence of liquid in the chamber 11. The withdrawal of said trapped portions of the chamber 11 with or without withdrawal of such liquid portions as may be contained within the body 75

is rendered most difficult by the assemblage of elements, as heretofore described. Should one attempt to pour the trapped contents from within in the chamber 11, as by tipping the container, the contents of the body portion 1 would flow out also. Thus, a refilling or meddling with the container or its original contents would be indicated to a user or purchaser of the goods contained in a container embodying the features of my invention, first, by the position of the valve, whether open or closed, second, the entrapment of portions of liquid within the chamber 11, or third, the incomplete and partial quantities contained in view of the capacity of the container.

15 The assemblage of elements 8 and 10 and stems 12 and 30 may be inserted and positioned within in the throat by any suitable method as the flexibility of the elements 8 and 10 permits considerable latitude of manipulation during installation. 20 If desired, however, the throat 2 may be formed of two connectable units 36 and 38, the unit 36 being integral with the body portion 1 and the unit 38 having the lip 3 and being joinable with the unit 36 along a joint line 39. Some suitable bond 25 40 may be provided along the joint line 39 to maintain the units 36 and 38 in assembled relation. Thus, the packer of the original contents 5 may place the contents within the container, insert the assemblage of elements 8 and 10 and 30 stems 12 and 39 into the throat unit 36 and bond the unit 38 to said unit 36 to thus speedily fill the container and install the assemblage.

The modified form of construction illustrated in Figs. 4 and 5 of the accompanying drawings 35 has a liquid containing body portion 58, a throat portion 51 like unto the body and throat portions 1 and 2 of the preferred form. The throat portion 51 is interiorly divided by discular wall elements 52 and 53, similarly as do the elements 8 40 and 10 of the preferred structure to form a trapping chamber 54 like the chamber 11 and an outer throat 55 like the outer throat 13. The outer throat 55 communicates with the trapping chamber 54 through a sleeve stem 56 which extends through and is seated in an opening 57 formed in the element 53. The stem 56 has an end opening 58 in the outer throat, the edges of which are provided with side slots or openings 59 for purposes hereinafter described. The interior 45 50 of the containing body 58 communicates with the outer throat through a passageway formed in a pipe or stem 60. The stem 60 extends through said stem 56, in concentric relation thereto, and is slidably mounted in an opening 61 formed in the element 52. The inner end of the stem 60 is closed and is provided with side openings 62 communicating with the passageway of the stem. The outer end of the stem 60 is closed and provided with a header 64 having a 55 flared portion 65. The diameter of the flared portion 65 is preferably slightly less than the inner diameter of the throat portion 55. Side openings 66 are formed in the stem 60 proximate to said header 64. The stem 60 may be further provided with a dish-shaped portion 68 formed preferably integral with said stem and disposed in slightly spaced relation to the openings 66 and overhanging the end opening 58 of the stem 56. Preferably, the diameter of the dish-shaped portion is slightly less than the inner diameter of the outer throat 55.

70 Thus, in use and operation during original packaging of the contents of the liquid containing body 58, the elements 52 and 53 may be installed in said throat portion, the stem 60 located with

reference to said element 52 so that the openings 62 are closed by portions of said element 52 surrounding the opening 66 as illustrated in Fig. 4 to thus form a valve relation with said openings and to prevent escape of the contents into the throat portion during shipment and handling. When it is desired to dispense the contents of the body portion, the stem 60 is moved inwardly with respect to the body 58 by manually pressing against said header 64 to uncover the openings 62 and 10 locate the parts in positions as illustrated in Fig. 5. When the stem 60 has been thus moved, it will be noted that the end opening 58 is closed by the dish-shaped portion 68 which acts to prevent entrapment of portions of the original contents during dispensing tippings and pourings of the container. The dimensions of the header 64 and dish-shaped portion 68 relative to the dimension of the throat are such as to prevent insertion of tools or other appliances into the throat and below said header and dish-shaped portion and thereby prevents tampering with the parts within in said throat and ready refilling of the container.

When, however, an attempted refilling of the container is effected, as by pouring the refilling liquid into the outer throat, portions of the refilling liquid flow from the outer throat through the slot openings 66 and the passageway of the stem 56 into the trapping chamber 54 to entrap said portion and indicate said attempted refilling. 30

I claim:

1. A non-refillable container having a liquid containing body portion and an integral throat portion, the throat portion having an opening for dispensing quantities of a liquid contained in the body portion and conducted by the throat portion, a wall element supported in the throat and dividing the throat into an outermost and an innermost portion, a second wall element supported in the innermost throat portion in spaced relation to the first named wall element to form a chamber therebetween, a hollow stem having closed ends and a side opening at each end extending through said elements and chamber for conducting liquid from the body portion to the outermost throat portion, said stem located so that the opening of one end is located in spaced relation to the outermost surface of the first named wall element, a second hollow stem extending through the first named wall element and having an opening located more proximate to the outermost surface of the first named wall element for conducting liquid introduced in the outermost throat portion into said chamber to thereby indicate said introduction. 55

2. A non-refillable container having a liquid containing body portion and an integral throat portion, the throat portion having an opening for dispensing quantities of a liquid contained in the body portion and conducted by the throat portion, a wall element supported in the throat and dividing the throat into an outermost and innermost portion, a second wall element supported in the throat in spaced relation to the first named wall element to form a chamber therebetween, a movable hollow stem having closed ends and a side opening at each end extending through said elements and chamber to locate one end in the outermost throat portion so that said end's associated opening is located in spaced relation to the outermost wall of the first named element, a header supported by said last named end and adapted to restrict entry into said throat portion and to form a means for engaging the stem in moving the same, the other end of the stem extending into 75

- said containing body so that its associated side opening communicates with the interior of said containing body for conducting liquid from the body, a second hollow stem extending through the 5 first named wall element and having an opening located more proximate to the outermost surface of the first named wall element for conducting liquid introduced in the outermost throat portion into said chamber to thereby indicate said introduction.
3. A non-refillable container having a liquid containing body portion and a throat portion, the throat portion having a dispensing opening, a chamber formed in said throat portion intermediate and separating the interior of the body portion from the dispensing opening, a member having a passageway communicating between said chamber and said dispensing opening, a second member extending through the passageway of 10 said first named member, the chamber and into the interior of the body portion, said second member having a passageway communicating with said interior of the body portion and the opening of the throat portion for conducting the 15 liquid contents of the body portion to the dispensing opening and a dish-shaped element disposed proximate to said dispensing opening for receiving portions of the liquid remaining in the throat portion after the container has been tipped 20 for dispensing of the original liquid contents whereby the trapping of said liquid portions is prevented.
4. A non-refillable container having a liquid containing body portion and a throat portion, the 25 throat portion having a dispensing opening, a chamber formed in said throat portion intermediate and separating the interior of the body portion from the dispensing opening, a member having a passageway communicating between 30 said chamber and said dispensing opening, a second member extending concentrically through the passageway of said first named member, the chamber and into the interior of the body portion, said second member having a passageway communicating with said interior of the body portion and the dispensing opening, and means including a dish-shaped element for catching and retaining portions of the original liquid contents remaining at the dispensing point subsequent to a dispensing operation for preventing the flow of liquid from the passageway of the second member into the 35 passageway of the first member preventing trapping of the original contents in the chamber.
5. A non-refillable container having a liquid containing body portion and a throat portion, a wall located in the throat portion and dividing the throat into upper and lower portions, the upper portion of the throat having a dispensing opening, a second wall located in the throat intermediate the first named wall and the liquid containing body portion, the first and second named 40 walls forming a chamber intermediate and separating the interior of the body portion from the dispensing opening, a tubular member located in the first named wall and communicating between said chamber and said dispensing opening, a hollow stem extending concentrically through the passageway of said tubular member, said chamber, said second named wall and into the interior of the body portion, said hollow stem having closed ends and side openings in each 45 end thereof, the lower end of said stem being movable within said second wall to close the adjacent side openings when in one position and to open said side openings below said second wall when in another position for conducting 50 liquid contents of said body portion to said dispensing opening, and means for preventing the flow of liquid from said hollow stem into said tubular member to thereby prevent trapping of the original contents of said body portion in said 55 chamber.

MYER SIGMAN.
